FRAME FOR VERTICALLY SWINGING CONVEYERS

Orville E. Smith, Grand Rapids, Mich., assignor to Rapids-Standard Company, Inc., Grand Rapids, Mich., a corporation of Michigan

Application December 31, 1947, Serial No. 794,982

16 Claims. (Cl. 198—122)

1

This invention relates to a conveyor elevating mechanism and more particularly to one comprising a toggle mechanism operated by a rod of variable length and connected for changing the angular position of the conveyor bed with respect to the horizontal.

In the design of conveyor mechanisms it is necessary to provide one having the capacity for changing the conveyor bed from one position to another with respect to the horizontal. The difficulty involved in devising such a mechanism is complicated in part by the fact that it is desirable that the conveyor, when in its horizontal or contracted position, should have its bed as close as possible to the floor resulting in little conveniently available room for the installation of the operating mechanism. In order that the elevator structure, in one position be capable of extending to support the raised bed and, in another position, be stored within the conveyor body, it is necessary that the mechanism fold up into a compact mass as the conveyor bed is lowered into its horizontal position. Concentrically sleeved, hydraulic units are capable of performing this function but they are so costly to produce that the final product is uneconomical. It is, therefore, necessary to provide a mechanical linkage with the further limitation that the lines of force generated within the linkage, as the various parts thereof change their relative positions, must provide for easy operation of the unit. Further, the resulting unit must be easily operable by a manual crank or require a motor of reasonably small horsepower. At the same time the various parts designed to perform this service must be small enough to fit within the restricted area of the conveyor outline.

In addition to the requirements set out above, the unit must develop sufficient strength that the conveyor may be used for heavy loads without fear of structural failure, and it must be so balanced that the constantly shifting loads will not materially change its center of gravity. Furthermore, it must be rigid enough to eliminate any sway when in the raised or open position. All of these characteristics are necessary to provide a conveyor which is safe to operate.

The unit must be simple in order to reduce both the initial cost and to eliminate, as far as possible, the problem of subsequent breakdowns and the consequent delays and repair costs. Heretofore, solutions of one type or another have been found for each of these problems singularly, but, until the applicant's invention a mechanism providing a satisfactory solution for all of

2

these problems in combination did not exist. However, through my combination as herein disclosed an efficient conveyor elevating unit has been created.

5 It is therefore a primary object of my invention to provide a conveyor elevating mechanism capable of providing a wide latitude of inclined positions for the conveyor bed.

10 It is a further object of my invention to provide a mechanism such that it will occupy only a small area close to the supporting floor when the conveyor bed is in its horizontal position.

15 A still further object of my invention is to provide such a mechanism requiring a minimum of effort to operate.

An additional object of my invention is to provide a mechanism which is structurally simple, yet having high strength characteristics and capable of operation without side sway.

20 Another object of my invention is to provide an elevator mechanism having a maximum safety factor for the operator.

25 Still another object of my invention is to provide such a mechanism designed for efficient and economical fabrication.

Other objects and purposes of my invention will be apparent to persons acquainted with equipment of this type upon examination of the accompanying drawings and reading of the following disclosure.

In the drawings:

Figure 1 is an oblique view of my invention.

Figure 2 shows my conveyor elevator mechanism in partially extended position.

Figure 3 shows my conveyor elevator mechanism in fully extended position.

Figure 4 shows my conveyor elevator mechanism in fully closed or lowered position.

Figure 5 is a sectional view of my conveyor elevating mechanism as viewed from the plane V—V of Figure 2, but showing no part of the conveyor bed or bed supporting frame.

Figure 6 is a sectional view of my invention taken along the plane VI—VI of Figure 5 cutting all the parts except the driving shaft.

Figure 7 is a fragmentary, top, sectional view showing in section all the parts along the member of variable length except the driving shaft which is shown in full.

Figure 8 is a fragmentary, top, sectional view of the actuating screw, associated housing and the mounting therefor, the plane of the section cutting all parts except the actuating screw.

Figure 9 is a fragmentary view of my invention taken along the plane IX—IX in Figure 2.

Figure 10 is a sectional view taken along the plane X—X of Figure 9.

Figure 11 is an enlarged, fragmentary side view of one of the rocker plates, and directly associated parts, of my invention.

Figure 12 is a diagrammatic representation of the relative positions of the operating parts of my invention in open position.

Figure 13 is a diagrammatic representation of the relative positions of the operating parts of my invention in closed position.

Figure 14 is a side elevational view of my conveyor showing a modification of the supporting structure.

In accomplishing the objects and purposes of my invention I have provided a conveyor elevating mechanism utilizing a toggle linkage, one leg of which constitutes a triangle, pivotally supported at one corner, connected at another corner to the conveyor bed through the second leg of the toggle, and connected at the third corner to a threaded, extensible operating member. Changing the length of the threaded operating member causes the triangular leg to pivot on its support thereby operating the toggle for raising or lowering the conveyor body.

The terms "forward" and "rearward" will be freely used in the description of my invention and shall be taken to mean forward toward the raisable end of my conveyor, or the left hand side of Figure 2, and rearward toward the end of my conveyor having the support of fixed height. The terms "upper" and "lower" will be taken to refer to the conveyor as shown in Figure 2.

For illustrative purposes herein the conveyor is shown as having one end supported on the adjustable mechanism of my invention and the other end supported on a stand of fixed height. It will be understood that this is illustrative only and that the conveyor may be supported at both ends by vertically adjustable mechanisms, either or both of which may be that of my invention herein disclosed, or, alternatively, the end here shown as on the stand of fixed height may be supported directly on a fixed platform, such as a loading dock, or may even be supported on the floor, providing only that such support permits it to pivot as the conveyor bed is moved through varying positions with respect to the horizontal.

Referring specifically to the drawings, the numeral 1 refers to a conveyor bed pivotally mounted on its rearward end to a support stand 2 of height assumed for purposes herein to be fixed, and on its forward end to a support platform 3 by means of the elevating mechanism 4 and associated frame 5. Both the support stand 2 and the support platform 3 are mounted upon casters 6 (Figures 1 and 2).

The elevating mechanism consists of a pair of drag links 7, a pair of triangular rocker plates 8 and an adjustable member 9. Each of the drag links 7 at its upper end is welded to a tubular casing 10 (Figure 9). Each such casing is equal to one-half the space existing between the frame members 11 of the conveyor bed 1. This enables the casing to occupy the entire space between the frame members and prevent any lateral movement thereof. A supporting shaft 12 passes through each of the casings 10 and projects at each of its ends through suitable openings 83 in the frame members 11 (Figures 2 and 9). Lateral movement of the shaft is prevented by a cotter pin 13 on each end (Figures 2 and 9). The lengthwise position, on the conveyor bed, of this

pivot mounting will be described more fully hereafter.

The drag links 7 are formed from tubular stock with the lower end 14 of each link flattened to provide a substantially rectangular portion surrounding the pivot pin 15 (Figure 5). Each of the pivot pins 15 is rigidly attached to a drag link by welding or other suitable fastening means. A hole is provided through the pivot pin to receive the cotter pin 16.

The rocker plates 8 are triangular in shape and formed with beads 17 along a portion of each side extending inwardly toward the adjustable member 9 (Figures 2 and 11). These beads increase the compressive strength of the plates. At the link corner 18 of the rocker plates there is provided an opening surrounded by an annular boss 20 for receiving the pivot pin 15 of the drag link 7 (Figures 5 and 11). The annular boss 20 projects outwardly from the rocker plate 8 in the opposite direction to the bead.

At the mounting corner 21 of the rocker plate an annular mounting boss 22 is welded to the rocker plate and projects outwardly therefrom in the same direction as the boss 20 (Figures 2, 5 and 11). A threaded opening 23 for receiving a set screw extends through the boss 22 at a right angle to the central opening therein.

At the third, or operating, corner 24 of the rocker plate 8 another annular boss 25 (Figure 11) is welded to the plate extending in the opposite direction to the boss 20. A short shaft 26 seats within this boss and extends outwardly therefrom. This shaft 26 is rigidly fixed to the boss 25 by welding or other suitable attaching means and is provided with a cotter pin receiving opening near its projecting end. Substantially midway between the corners 18 and 21 of the rocker plate an opening 27 is provided through the plate (Figure 3). A tubular spacer 85 extends between the two rocker plates and a bolt 86, held by the nut 87 (Figures 5 and 11), passes through the openings 27 and the spacer 85. This spacer is located such that when the conveyor bed is in its position of maximum elevation it will not interfere with the adjustable member 9.

A bearing tube 28 passes through the boss 22 in each of the rocker plates 8 and is rigidly held against both axial and rotatable movement relative to the rocker plates by the set screw 29 inserted in the opening 23. A pivot shaft 30 passes through the bearing tube 28.

The frame 5 is a trapezoidal structure wherein each of the non-parallel sides 31 consists of 2 tubular rails 32 and 33 bent through a 90 degree arc on one of their respective ends (Figures 2 and 5). These rails are placed with their curved ends in opposite directions and welded together.

A structural spacer 34 is welded between the rails at each end. At the lower end of the frame the curved rails are welded to the tubular cross member 35.

A hinge shaft 36 passes through the center of the cross member 35 and projects from each end thereof a sufficient distance to pass through openings in the base brackets 37. The cross member 35 is of sufficient length to contact the base brackets 37 and thereby prevent any lateral movement. The support platform 3 is not described in detail in this application as it may be of any suitable construction, such as that disclosed in the co-pending application of Bert Woldring, Serial Number 577,793, filed February 14, 1945, entitled "Dolly," now Patent 2,452,978.

5

Substantially midway between the ends of the sides 31 a rectangular support plate 38 (Figures 1 and 2) is affixed between the rails 32 and 33 by welding and at such an angle to the centerline of the rails that the two plates are parallel and at a right angle to the cross member 35. Axially aligned openings 39 are provided in each plate (Figure 2). The ends of the pivot shaft 30 pass through the openings 39 and are rotatable therein. The bearing tube 28 abuts the plates 38 on each of its ends and is thereby held against axial movement.

A mounting bracket 40 (Figures 1, 2, 5 and 6), having an opening 41 in its forward end, is attached to each of the frame members 11 of the conveyor bed 1 by any suitable fastening means such as bolts 52 or rivets. Through the opening 41 in each of these brackets passes a tubular frame mount 42 for the frame 5. The end of the curved rail at the upper end of the side 31 of 15 the frame is welded to a frame mount 42 (Figure 6).

The frame mounts 42 pass through and rotatably support the yoke 43 by means of the openings 19 (Figures 5 and 6). Inside the yoke is a bevel gear 44 having a collar 45 separated from direct contact with the yoke by the washer 46. A further washer 47 is provided adjacent the side of the yoke away from the bevel gear and abuts the inner end of one of the frame mounts 42. A crank shaft 48 passes through the center of the frame mounts 42, the washers 45 and 47 and the bevel gear 44. A washer 49 seats on the crank shaft 48 adjacent the exterior surface of each bracket 42 and abutting the outer end of each of the frame mounts 42. One end of the crank shaft 48 extends outwardly from the bracket 42 to provide a mount for the crank handle 50. The crank handle 50 is separated from the washer 49 by the spacer 51 in order that the handle will clear the conveyor bed when operated.

The center of the yoke 43 is provided with an opening 53 to receive the threaded shaft 54 (Figure 7). Inside the yoke a bevel gear 55, having a diameter approximately double that of the bevel gear 44 but in other respects similar to it, is mounted on the threaded shaft 54 and separated from the yoke by the washer 56. Exterior of the yoke a thrust bearing 57 surrounds the shaft 54 and is separated from the yoke by the pressure plate 58. A tubular shield 59 of sufficient diameter to receive the thrust tube 60 (Figures 7 and 8) surrounds the threaded shaft 54. A collar 61 having a portion 62 of sufficiently reduced diameter to fit within the tubular shield 59 is rigidly attached to the shaft 54 by the tapered pin 63.

The internal opening of the thrust tube 60 is of sufficient diameter to receive the threaded shaft 54. A nut 54 (Figure 8) having a reduced portion received into the thrust tube 60 is welded to the end of the thrust tube received into the shield. Both the nut 64 and the shaft 54 are equipped with any type of thread suitable for power delivery such as an Acme type thread. The threading on the shaft 54 extends from its rearward end forwardly to a point inside the shield 59 adjacent to the collar 61. A tapered opening 65 designed to receive a stop pin is provided in the end of the threaded shaft.

The forward end of the thrust tube 60 is welded to a substantially U-shaped saddle 66 comprising an end piece 67 and sides 91a, 91b, 91c and 91d. The sides 91c and 91d are set at

6

an angle of substantially 30° to the end piece 67 and join the end piece 67 to the sides 91a and 91b which are at a right angle to the end piece. A pair of compression bars 92 connect the side pieces 91c and 91b on their top and bottom surfaces respectively. The sides and the end piece may be made from separate parts assembled by welding but preferably they are formed from a single part by bending. The compression bars are assembled to the sides 91a and 91b by welding. The thrust tube 60 is affixed thereto at the center of the end piece 67 (Figure 5). Axially aligned openings 68 are provided in the sides 91a and 91b of the saddle 66 parallel to the thrust tube to rotatably receive the shafts 26 of the rocker plates 8 (Figures 8 and 11). The various parts of the conveyor may be made from any suitable material but to develop maximum strength and to facilitate the use of a welded construction, steel is preferred.

By experimentation it has been found that, although other dimensional relationships will operate with varying degrees of effectiveness, one highly satisfactory proportioning of the parts of the adjusting mechanism is as follows: The spacing between the pivot point of the supporting frame 5 at the bracket 40 and the mounting point of the pivot shaft 30 on the supporting frame 5 is 24 inches, and a similar spacing exists between the point of attachment of the drag links 7 and the frame members 11 and a point on the frame in vertical alignment with the crank shaft 48, when the conveyor bed is in a horizontal position. A vertical spacing of 2 inches between the crank shaft 48 and the plane of the drag link attachment point on the frame members 11 has been found desirable in this embodiment to permit the rocker plates 8 to rotate without interference with the conveyor bed. When these dimensions are used, the optimum dimension on the rocker plates 8 between the center of the opening at the mounting corner 21 and center of the opening at the link corner 18 is 14 inches and the effective length of drag link is 16½ inches. These dimensions, of course, may be increased or decreased while retaining the mechanical efficiency afforded by them if substantially the same proportions between them are maintained.

50 Assembly

The bevel gear 55 is assembled to the threaded shaft 54 by passing it over the unthreaded end and attaching it thereto by insertion of the pin 69 through the collar of the gear and a suitable hole 55 in the shaft (Figure 7). The pin is held in place by any suitable arrangement such as a head 70 on one end and a cotter pin 71 on the other. The spacing washer 56 is then passed down the threaded shaft 54 and the latter installed in the opening 53. The frame mounts 42, together with the frame 5 welded thereto, are inserted in the openings 19 and the resulting assembly is installed on the conveyor frame 11 by insertion of the frame mounts 42 into the openings 41 in the mounting brackets 40 which are in turn attached to the frame members 11 by the installation bolts 52. The bevel gear 44 together with the spacing washer 46 is held in place and the crank shaft 48 is inserted through one frame mount 42, the washer 41, the bevel gear 44, the spacing washer 46 and the second frame mount 42. The washers 49 are put in place, the spacer 51 slipped onto the end of the shaft 48, and the cotter pins 72 and 73 are then installed to prevent further lateral

movement of the crank shaft 48. The retaining pin 74, similar to pin 69, is then inserted through appropriate openings in the collar 45 of the bevel gear 44 and the crank shaft 48. A further cotter pin 75 is installed in an appropriate opening in the shaft 48 to retain the washer 47. The two washers 49, held in fixed axial relationship to the crank shaft 48 by the cotter pins 72 and 73, prevent lateral movement of the shaft 48, yoke 43, and associated assembly. The crank handle 50 is seated on the end of the shaft and held into place by the set screw 76. This completes the assembly of the parts in the area proximate to the conveyor bed.

To complete the assembly of the adjustable member 9 the pressure plate 58, thrust bearing 57 and collar 61 are slipped into place along the threaded shaft 54. The collar 61 is held against rotation relative to the threaded shaft by installation of the tapered pin 63. This pin is so made that it will snugly seat in the tapered opening 77 without projecting out of either end thereof. The shield 59 is then fitted over the reduced portion 62 of the collar and fixedly attached thereto by the set screw 78. To prevent subsequent loosening of this set screw it may be tackwelded to the outer surface of the shield.

The welded assembly including the saddle 66 and the thrust tube 60 are then added to the existing unit by threading the nut 64 onto the threaded shaft 54. When the threaded shaft has passed through the nut 64 a sufficient distance to align the opening 65 for the stop pin 79 with the opening 80 in the thrust tube, the tapered stop pin 79 is installed and peened down to prevent subsequent disengagement. The length of the shield 59 is such that when the openings 65 and 80 are aligned they will not be covered by it.

The rocker plates 8 are attached to the saddle 66 by inserting one of the shafts 26 in each of the openings 68 (Figures 8 and 11). The washers 81 and cotter pins 82 complete the assembly, holding the sides 91a and 91b of the saddle firmly but rotatably against the bosses 25.

The tubular bearing shaft 28 is passed through the boss 22 in each of the rocker plates 8 (Figures 5 and 11). The opening in the bearing shaft 28 is then aligned with the opening 39 (Figure 2) in each of the plates 38 and the pivot shaft 30 inserted therethrough and thereafter held against axial movement by a washer 89 and a cotter pin 90 on each of its ends. The set screw 29 in each of the bosses 22 is tightened against the bearing shaft 28.

The drag links 7 with a tubular casing 10 welded to the upper end of each of them are aligned with suitable openings 83 in the frame members 11 of the conveyor bed 1 and the supporting shaft 12 is inserted through the openings 83 in the frame and the center of the tubular casings 10 (Figure 2). The supporting shaft is held against lateral movement by the cotter pins 13 on each end. The pin 15 on the lower end 14 of each of the drag links is then passed through the boss 20 in each of the rocker plates 8 and the washer 84 together with the cotter pin 16 installed. The tubular spacer 85 is aligned with the openings 27 in the rocker plates 8 and the bolt 86 inserted (Figures 2, 3, 5 and 11). The nut 87 is tightened, clamping the rocker plates tightly against the ends of the spacer 85 and serves to prevent deflection of the rocker plates either inwardly or outwardly. This completes the assembly of the elevating mechanism and its associated parts.

The brackets 40 are located forward of the

center of the conveyor bed and the openings 83 are located approximately midway between the brackets 40 and the forward end of the conveyor. This position, however, is only a preferred example of which there can be many variations according to the requirements of the conveyor. The point of attachment of the drag links 7 to the frame 5 must be so located that when the loads are placed on the forward end of the conveyor there will be no tendency of the conveyor belt to pivot about the elevating mechanism. On the other hand, the point should not be located farther forward than necessary because the further the openings 83 are spaced from the brackets 40, the less the distance the conveyor bed can be elevated.

Each of the parts assembled to rotate in relationship to each other are designed to provide sufficient spacing between them to permit easy movement but yet prevent any looseness due to excessive gaps. This is necessary to provide a structure which will both resist wear and at the same time have no side sway.

25

Operation

When the conveyor bed is in its lowered or horizontal position (Figure 4) the adjustable member 9 is in its fully retracted position and the rocker plates are rotated rearwardly about their mountings to the frame 5 such that the link corner 18 of the rocker plates is rearward of and below the mounting corner 21. To elevate the forward end of the conveyor, the crank handle 50 is turned imparting rotation to the threaded shaft 54 thereby forcing the saddle 66 away from the yoke 43. This causes the rocker plates to be pivoted about the pivot 30 (Figure 2) in such a manner as to move the link corner 18 of the rocker plates upwardly and forwardly. This in turn forces the drag links 7 upwardly raising the forward end of the conveyor bed 1. As the conveyor bed is raised it pivots about the rearward support stand 2 at its point of attachment 88. Figure 2 shows this operation in partially completed condition and Figure 3 shows the conveyor bed fully elevated. The tightness of the threads on the shaft 54 together with the friction incident to the gears and crank shaft are sufficient to prevent the shaft 54 from being caused to rotate by the weight of the conveyor. This eliminates the necessity of any locking mechanism in connection with the crank shaft or threaded shaft.

The cross member 35 at the lower end of the frame 5 rotates about the hinge shaft 36 permitting the forward support platform to move as the spacing between it and the rear support stand changes.

The tubular mounts 42 rotate within the openings 41 permitting the frame 5 and the conveyor bed 1 to change their relative positions. The yoke 43 is likewise free to rotate about the tubular mounts 42 as the extensible member 9 changes its angular position. By extending the tubular mounts 42 through the brackets 40, the loads imposed by the frame 5 are partially carried by the mounts 42 and the remainder distributed to the crank shaft 48 over an extended area thereby reducing both the possibility of deflection and the wear on the crank shaft. This arrangement also helps to distribute the loads imposed through the yoke 43 by the operation of the adjustable member 9. The same distribution of loads and reduction of wear is effected

by the use of the bearing shaft 28 to support the rocker plates 8.

The shield 59 serves to cover the threaded shaft 54 and prevent dust and other matter from entering the threads.

In Figures 12 and 13 the relative positions of the conveyor bed 1, mounting bracket 40, adjustable member 9, drag links 7, supporting frames 5, and rocker plates 8 are diagrammatically shown in two positions of adjustment, namely, when the conveyor bed is fully raised and when it is fully lowered. It is seen from these diagrams that the rocker plates 8 are caused to pivot about their mounting corners 21 by moving the operating corner 24 toward or away from the bracket 40, thus actuating the toggle comprising the drag links and that part of the triangular plates between the link corner 18 and the mounting corner 21, while the mounting corner 21 and the supporting point 12 on the conveyor bed are each held in constant, spaced relationship with respect to the bracket 40. By use of the triangular rocker plates the point of attachment of the adjustable member is separated from the pivot point 18 of the toggle making it possible to operate the toggle through a greater range of angular relationships without producing such relative positions of the toggle and the adjustable member that the forces necessary for operation become excessive.

By setting a portion of the sides of the saddle 66 at an angle to both the end piece 67 and sides 91a and 91b the tendency of the end piece 67 to deflect is eliminated. The compression bars 92 prevent the saddle from collapsing inwardly.

Although the conveyor as described and shown in this application utilizes an elevating mechanism on only one end, it is possible to eliminate the rear support stand and substitute my elevating mechanism so that the conveyor will be equipped with such an elevating mechanism on both of its ends. The manual operation of the crank shaft can be easily changed to power by substituting a gear, pulley or sprocket gear suitable for a chain and suitably engaging a motor thereto.

It may also be desirable under some circumstances to attach the threaded shaft 54 to the saddle 66 in such a manner that it is held against rotation and to attach the nut 60 operatively to the bevel gear 55 such that the nut 60 rather than the threaded shaft 54 is rotated to cause extension and retraction of the adjustable member 9.

The support for the conveyor may be so modified that the leg upon which the elevating mechanism 4 is mounted becomes a fulcrum (Figure 14). To do this a supporting stand 100 of fixed height consisting of two rigid, triangular, vertical sides 101 and the horizontal base 102 is substituted for the supporting frame 5. The rear end of the conveyor is then left without support either by a floor, platform or stand. In this manner the expansion and contraction of the adjustable member 9 causes the conveyor bed to pivot about the crank shaft 48 which in this modified construction is a point of fixed height. The mechanism of this invention thus functions as means to adjust the position of the conveyor frame with respect to the horizontal while a point intermediate its ends is maintained at a fixed height.

It will be evident that various other modifications may be made in the structure herein disclosed but such obvious variations will all be included within the scope of my hereinafter ap-

pended claims, excepting as said claims may by their own terms expressly provide otherwise.

I claim:

1. For a conveyor bed pivotally supported at one end and having a supporting leg pivotally mounted in fixed relation to the conveyor bed supporting the other end of said bed, and adjusting means associated with said supporting leg adjusting the height of said other end of said bed, the improvement in said adjusting means comprising: a pair of members constituting a toggle unit connecting said supporting leg and said conveyor bed at points on each thereof removed from the point of pivotal mounting of said supporting leg; one of said members having a portion providing an attachment point between the hinge point of said toggle and the point of attachment of said toggle unit to said leg and spaced substantially from a line passing through said hinge point and the end of said one member away from said hinge point in a direction away from said point of attachment of said supporting leg, and said conveyor bed when said toggle is in open position; means of variable length pivoted at one of its ends at said point of pivotal mounting of said supporting leg and at the other of its ends pivoted at said attachment point and operable for opening and closing said toggle unit.

2. A conveyor having a bed pivotally supported at one end thereof, a supporting leg pivotally mounted in fixed relation to the conveyor bed supporting the other end of said bed, and means associated with said supporting leg adjusting the height of said other end of said bed, the improvement in said adjusting means comprising: a pair of members constituting a toggle unit connecting said supporting leg and said conveyor bed at points on each thereof removed from the point of pivotal mounting of said supporting leg; an arm on one member of said toggle unit extending in a direction away from said leg when said toggle is in open position and outwardly from a line passing through the hinge point of said toggle unit and the end of said one member away from said hinge point; a member of variable length mounted to the outward end of said arm for opening and closing said toggle unit upon extension and retraction of said member; means for extending and retracting said member of variable length.

3. An adjustable stand for a conveyor having a vertically adjustable bed, comprising: a supporting leg pivotally mounted in fixed relation to the conveyor bed and describing an acute angle therebetween when said conveyor bed is in raised position; said supporting leg and said conveyor bed being substantially parallel when said conveyor bed is in maximum lowered position; a pair of links constituting a toggle unit, the first of said links being pivotally attached to said conveyor bed at a point removed from said point of attachment of said supporting leg, the second of said links being pivotally attached to said supporting leg at a point removed from the point of its attachment to the conveyor bed; a member of variable length anchored at one of its ends adjacent the vertex of said acute angle and mounted at the other of its ends to one of the links of said toggle unit spaced outwardly in the plane of movement of said toggle unit from a line passing through the hinge point of said toggle unit and the end of said link away from said hinge point operable for causing said toggle unit to open and close whereby said conveyor bed

may be caused to change its angle of elevation between the limits of horizontal and 75°.

4. An adjustable stand for a conveyor as described in claim 3 in which: the spacing between the point of pivotal attachment of the supporting leg and the point of pivotal attachment of said second link to said supporting leg is equal to the spacing between the point of pivotal attachment of said first link to said conveyor bed and the point on said conveyor bed in a plane including the point of pivotal attachment of said first link to said conveyor bed and parallel to the longitudinal plane of the conveyor bed closest to the point of pivotal mounting of said supporting leg.

5. An adjustable stand for a conveyor as described in claim 3 in which: the point of pivotal mounting of the leg is spaced from the point on said conveyor bed in a plane including the point of pivotal attachment of said first link to said conveyor bed and parallel to the longitudinal plane of the conveyor bed closest to the point of pivotal mounting of said supporting leg a distance constituting a minor fraction of the distance between the point of pivotal attachment of the supporting leg and the point of pivotal attachment of the second link to said supporting leg.

6. An adjustable stand for a conveyor having a bed pivotally supported at one end, said stand comprising: a supporting leg pivotally mounted in fixed relation to the conveyor bed proximate to a point midway between the ends of said conveyor bed; a pair of links constituting a toggle unit, one of said links being pivotally attached to said conveyor bed substantially midway between said supporting leg and the other end of said conveyor bed, the other of said links being pivotally attached to said supporting leg at a point removed from its point of pivotal mounting; an arm on one member of said toggle unit extending outwardly from a line connecting the hinge point of said toggle unit and the end of said one member away from said hinge point in a direction away from said leg when said toggle unit is in open position; a member of variable length operatively arranged for causing said toggle unit to open and close.

7. An adjustable stand for a conveyor having a bed, comprising: a supporting frame pivotally mounted on one of its ends in fixed relation to the conveyor bed and, on the other of its ends to floor engaging means; a pair of drag links; a pair of triangular rocker plates pivotally attached at one of their corners to said pair of drag links, the whole constituting a toggle unit; said drag links at the end remote from said rocker plates pivotally attached to said conveyor bed; said rocker plates at another of their corners pivotally mounted to said supporting frame; a thrust member threaded at its one end and pivotally attached at its other end to the third corner of said rocker plates and held against rotation about its longitudinal axis; a rotatable shaft having threaded means engaging said threaded means of said thrust member; means for rotating said shaft; said thrust member and said shaft together constituting a member of variable length, said member of variable length in extended position holding said toggle unit open and said supporting leg and conveyor bed apart at a wide angle with respect to each other, and in the retracted position holding said toggle unit in a closed position and said supporting leg and said

conveyor bed at a small angle with respect to each other.

8. An adjustable stand for a conveyor having a bed, comprising: a supporting frame pivotally mounted on one of its ends in fixed relation to the conveyor bed at a point substantially midway between the ends of said conveyor bed and on the other of its ends to floor engaging means; a pair of drag links; a pair of triangular rocker plates pivotally attached at one of their corners to said pair of drag links, the whole constituting a toggle unit; said drag links at the end remote from said rocker plates pivotally attached to said conveyor bed at a point substantially midway between the point of pivotal mounting of said supporting leg and the end of said conveyor bed; said rocker plates at another of their corners pivotally mounted to said supporting frame at a point substantially removed from the end of said supporting frame pivoted to said conveyor bed; a thrust member threaded at its one end and pivotally attached at its other end to the third corner of said rocker plates and held against rotation about its longitudinal axis; a rotatable shaft having threaded means engaging said threaded means of said thrust member; said thrust member and said shaft together constituting a member of variable length; means for rotating said shaft for causing said member of variable length in extended position to hold said toggle unit open and said supporting leg and conveyor bed apart at a wide angle with respect to each other, and in the retracted position to hold said toggle unit in a closed position and said supporting leg and said conveyor bed at a small angle with respect to each other.

9. An adjustable support for a conveyor bed comprising: a supporting frame of fixed height and having a base of sufficient length to give the conveyor bed longitudinal stability; said conveyor bed proximate to a point midway between its ends pivotally attached to said supporting frame; a pair of links constituting a toggle unit, one of said links being pivotally attached to said conveyor bed at a point substantially removed from said point of attachment of said supporting stand; the other of said links being pivotally attached to said supporting leg at a point removed from the point of its attachment to the conveyor bed; an arm mounted on one link of said toggle unit and extending outwardly therefrom in a direction parallel to the plane of movement of said toggle unit; a member of variable length pivotally mounted on one of its ends to said arm at a point substantially spaced from the longitudinal axis of said one link for causing said toggle unit to open and close.

10. For a platform pivotally supported at one end and having a supporting leg pivotally mounted in fixed relation to said platform supporting the other end of said platform, and adjusting means associated with said supporting leg for adjusting the height of said other end of said platform, the improvement in said adjusting means comprising: a pair of members constituting a toggle unit connecting said supporting leg and said platform at points on each thereof removed from the point of pivotal mounting of said supporting leg; an arm mounted on one member of said toggle unit and extending outwardly therefrom in a direction parallel to the plane of movement of said toggle unit; means pivotally attached to said arm at a point substantially removed from the longitudinal axis of

13

said one member for opening and closing said toggle unit.

11. An adjustable stand for a platform, comprising: a supporting frame on one of its ends pivotally mounted in fixed relation to said platform and, on the other of its ends to floor engaging means; a pair of drag links; a pair of triangular rocker plates pivotally attached on one of their corners to said pair of drag links, the whole constituting a toggle unit; said drag links at the end remote from said rocker plates pivotally attached to said platform; said rocker plates at another of their corners pivotally mounted to said supporting frame; a thrust member threaded at its one end and pivotally attached at its other end to the third corner of said rocker plates and held against rotation about its longitudinal axis; a rotatable shaft having threaded means engaging said threaded means of said thrust member; means for rotating said shaft; said thrust member and said shaft together constituting a member of variable length, said member of variable length in extended position holding said toggle unit open and said supporting leg and platform apart at a wide angle with respect to each other, and in the retracted position holding said toggle unit in a closed position and said supporting leg and said platform at a small angle with respect to each other.

12. An adjustable stand for a platform as described in claim 11 wherein said triangular rocker plates describe an isosceles triangle; said third corner of said triangle being the vertex between the sides of equal length of said rocker plates.

13. An adjustable stand for a conveyor having a frame and a supporting leg pivotally mounted on one of its ends in fixed relation to said frame and on the other of its ends to floor engaging means, the improvement in said stand including: a pair of links constituting a toggle unit connecting said supporting leg and said frame at points on each thereof removed from the point of pivotal mounting of said supporting leg to said frame; a member of variable length mounted for opening and closing said toggle unit; an arm on one link of said toggle unit and extending outwardly therefrom in a direction parallel to the plane of movement of said toggle unit; said member of variable length pivotally mounted on one of its ends to said arm at a point substantially spaced from the longitudinal axis of said link

14

whereby a moment may be generated by the interaction of said arm and said member of variable length for urging said toggle unit to open when said toggle unit is closed and the links of said toggle unit are substantially parallel.

14. An adjustable stand for a conveyor as described in claim 13 wherein said member of variable length is pivotally mounted at the other of its ends to said frame adjacent said pivotal mounting of said frame and said supporting leg.

15. An adjustable stand for a conveyor described in claim 13 wherein said member of variable length at the other of its ends is pivotally mounted to said conveyor co-axially with said point of pivotal mounting of said frame and said supporting leg.

16. An adjustable stand for a conveyor having a frame, a supporting leg pivotally mounted in fixed relation to said frame and a pair of links constituting a toggle unit, the first of said links being pivotally attached to said frame at a point removed from said point of attachment of said supporting leg, the second of said links being pivotally attached to said supporting leg at a point removed from the point of its attachment to said frame, the improvement in said stand including: one of said links having a portion thereof projecting in the plane of movement of said toggle unit substantially outwardly from a line passing through the hinge point of said toggle unit and the pivotal mounting at the other of the ends of said one link; means attached to the outward end of said projecting portion of said one link for causing reciprocating rotative movement of said one link about its pivotal mounting at the said other end of said link.
